UNITED STATES PATENT OFFICE.

STEPHEN WOODARD, OF DELANO, MINNESOTA, ASSIGNOR OF ONE-HALF
TO ALBERT P. WOODARD, OF SAME PLACE.

SHINGLING-BRACKET.

SPECIFICATION forming part of Letters Patent No. 292,458, dated January 22, 1884.

Application filed November 2, 1882. Renewed December 27, 1883. (No model.)

To all whom it may concern:

Be it known that I, STEPHEN WOODARD, of Delano, in the county of Wright, and in the State of Minnesota, have invented certain new and useful Improvements in Shingling-Brackets; and I do hereby declare that the following is a full, clear, and exact description thereof, reference being had to the accompanying drawings, and to the letters of reference marked *to* thereon, making a part of this specification.

This invention relates to certain improvements in shingling-brackets; and it has for its objects to provide a bracket which may be readily attached to the roof, which will not be liable to tip backward or accidentally knocked loose while in use, and to provide an improved joint for the supporting-arm, and an improved beam and curved upright to support the outer end of the supporting-arm and act in conjunction with the base or foot to clamp the device to the roof, as more fully hereinafter specified. These objects I attain by the means illustrated in the accompanying drawings, in which—

25 Figure 1 represents a perspective view of my improved bracket complete, and Fig. 2 a vertical sectional view thereof on the line *x x* of Fig. 1.

The letter A indicates a metallic arm extending from a short standard, B, on the foot-piece or base C. The foot-piece or base C is provided with a toe, D, in front, which is adapted to be inserted between two shingles and a heel, E, which extends down on one of the shingles to prevent the device from tipping backward. The upper end of the arm A is slotted, as indicated, for the purpose hereinafter explained.

The letter F indicates a short metallic beam, having cast with it at one end a curved upright, G, which passes through a slot in the supporting-arm G'. The said beam and supporting-arm are pivoted in the arm A by means of a suitable bolt forming a knuckle-joint, which permits the beam and curved arm and the supporting-arm to be moved inde-

pendently of each other. The curved arm is provided with apertures H at suitable intervals, and the supporting-arm with an aperture, I, through which a bolt may be passed 50 to secure the arm in desired position to suit the pitch of the roof. The beam has cast with it lateral projections K, which straddle the arm A, and are provided with prods L, which take into the shingle and hold the device to the roof. The beam is also provided with a slot, M, through which projects a standard at the lower end of the arm A, the said standard being provided with an aperture, through which may be passed a nail or pin to 60 prevent the parts from being accidentally displaced when in use.

The device is attached to the roof between the shingles in the usual manner, two or more of said devices being employed, upon which 65 a board is supported, forming a shelf upon which the workman may rest while shingling.

Having thus described my invention, what I claim, and desire to secure by Letters Patent, is—

1. In combination with the standard B, mounted on a suitable base, and the arm A, formed thereon, the beam M, pivoted to said arm and having lateral prodded projections adapted to straddle the arm, and the standard projecting 75 from said arm through a slot in the beam, and provided with an aperture for a pin or bolt, substantially as set forth.

2. In combination with the arm A, secured to the standard B on the base and slotted at 80 its end, the beam M, carrying the curved arm G, and the supporting-arm G', both pivoted in the slot, substantially as and for the purposes specified.

In testimony whereof I affix my signature, 85 in presence of two witnesses, this 25th day of October, 1882.

STEPHEN WOODARD.
